UNITED STATES PATENT OFFICE.

JAMES L. HAMILTON, OF GRAND JUNCTION, COLORADO.

ORCHARD-HEATER.

1,094,401.

Specification of Letters Patent. Patented Apr. 21, 1914.

Application filed May 21, 1913. Serial No. 769,002.

To all whom it may concern:

Be it known that I, JAMES L. HAMILTON, a citizen of the United States, residing at Grand Junction, in the county of Mesa and State of Colorado, have invented a new and useful Improvement in Orchard-Heaters, of which the following is a specification.

My invention relates to improvements in orchard heaters adapted for the efficient and semismokeless combustion of all of the many varieties of fuel oils derived from petroleum from different sections of the country.

The object of the present improvement is to provide a heater having a large fuel capacity and having means whereby the surface combustion of the fuel within the reservoir may be localized and air for such local combustion supplied in such a manner that the combustion will remain substantially uniform until the fuel is entirely consumed.

The preferred form of construction of my improved orchard heater is shown in the accompanying drawing, in which:

Figure 1 is a longitudinal sectional view 25 of the heater in operation. Fig. 2 is a cross-section view on the line 2—2 of Fig. 1 showing the arrangement of the air draft tubes. Fig. 3 is a top plan view showing the damper for regulating the admission of air into the 30 combustion chamber through the air draft tubes.

Similar reference characters refer to similar parts in each of the views.

There is an increasing demand for orchard 35 heaters having a much larger fuel storage capacity than has been usual heretofore, in order to reduce the labor and expense of frequent refilling of the heaters during the frost period.

40 The cheaper class of fuel oils which are necessarily used in orchard heaters contain, especially in the extreme west and many sections of the south, large percentages of asphaltum. In the usual types of heaters 45 heretofore generally employed the combustion of the fuel is entirely from the surface. As the combustion proceeds and the surface of the fuel is thereby lowered, less air reaches the surface and the combustion is 50 thus made less efficient and complete. This condition also results in the early combustion of the more volatile constituents of the fuel oil whereby a very poor and lean grade of fuel is left in the lower part of the reservoir, sometimes amounting to twenty-five

per cent. of the original amount, in the form of asphaltum residuum which is practically incombustible with the limited air supply then available. With the increase in size and fuel storage capacity of orchard heaters, it has been found more difficult to control and regulate the surface combustion which should be confined to a limited area of the surface of the fuel and continue at an efficient and substantially uniform rate as the 60 surface is lowered by combustion.

My improved heater comprises a fuel reservoir 5 which is preferably made tapering as shown so a number of reservoirs may be closely packed or "nested" for shipment 70 and storage. A cover 6 is provided which is removably fitted to the top of the reservoir. For the purpose of confining the combustion of the fuel in the reservoir to a definite and limited area of its surface a combustion compartment is provided. This consists of a tapering tubular compartment 7 preferably located at one side or end of the fuel reservoir. Its entire top is open while it is provided with openings 8 at its lower end to admit oil from the main reservoir therein. The upper end of the combustion compartment 7 extends above the surface of the fuel in the reservoir at all times.

80 A collar 9 is secured to an opening in the cover 6 being preferably located at the opposite side of the fuel reservoir from the combustion compartment 7. This collar 9 is provided with a series of draft openings 10 near its base. A tapering draft tube or 90 chimney 11 is removably fitted to the collar 9, and is provided with numerous air inlet openings 12 at its upper and smaller end. A central air supply tube 13 having numerous openings 14 is provided for the purpose of admitting air to the central part of the burning gases within the chimney 11 in order to insure more complete and smokeless combustion. Air is admitted to the lower end of this air supply tube through a 100 horizontal tube 15 which extends through the side walls of the reservoir and is provided with openings at each end. This construction serves to heat the air during its passage through the cross tube 15 before it 105 enters the flame, thereby increasing the efficiency of the combustion.

110 For the purpose of confining the initial combustion of the fuel to that portion of the surface area inclosed by the combustion

chamber, and supplying the air required in such a manner as to maintain a substantially uniform rate of combustion until the fuel is entirely consumed, a series of draft openings 16 are provided in the cover 6 which are provided with air inlet tubes 17 of varying lengths which extend down into the combustion compartment 7, the longest reaching nearly to the bottom of the oil reservoir. A 10 pivoted damper 18 is provided whereby the draft openings 16 may be opened or closed at will.

When it is desired to use the heater the fuel reservoir should be filled with oil to a 15 point just below the upper edge of the combustion compartment 7 as shown by the upper broken line in Fig. 1. The pivoted damper should then be moved to its extreme position toward the left as shown by the 20 broken lines in Fig. 2, thereby uncovering all of the draft openings 16. A small quantity of gasoline may now be injected through the left hand opening 16 onto the surface of the fuel within the combustion compartment 25 which can then be readily ignited whereupon the burning gasoline will soon ignite the fuel oil. Only the first or left hand draft opening 3 is to be used at the beginning of the combustion when the reservoir 30 is nearly full, and a draft tube is not required for this opening as the inrush of the air carries it down to the surface. When the oil has been consumed down to the level shown in the drawings, the lower end of the 35 shortest draft tube, being the left hand one in Fig. 2, is uncovered, and air will then be drawn down through this tube close to the surface of the fuel and if the first opening be closed by the pivoted damper 18, as shown 40 in Fig. 3, the inrush of the air through the draft tube will have considerable velocity and produce something of a blow-torch effect. As the combustion proceeds and the surface level of the oil is thereby further 45 lowered, the longer draft tubes are successively brought into action in the same manner. Since the active surface combustion of the fuel is confined within the area inclosed by the walls of the combustion chamber 7, 50 and the fresh oil to replace that thus consumed is always admitted at the bottom, the oil thus more nearly maintains its original quality and specific gravity until substantially all consumed, so that lower grades of 55 oil may be successfully burned in this heater than has been practical heretofore.

The gases formed by the preliminary combustion in the combustion compartment 7, are drawn over and upward through the 60 draft tube or chimney 11 where sufficient air is supplied through the openings 10, 14 and 12 and the horizontal cross tube 15 to make the combustion complete and smokeless.

What I claim as my invention is:

1. An orchard heater comprising a fuel 65 reservoir, a cover fitted on the fuel reservoir, a series of air inlet openings in said cover, a series of draft tubes of varying lengths extending downward from said air inlet openings, and a draft opening in the cover of 70 the fuel reservoir to allow egress for the generated gases.

2. An orchard heater comprising a fuel reservoir, a preliminary combustion compartment within the fuel reservoir, a cover 75 fitted on the fuel reservoir, a series of air inlet openings in said cover located directly above the combustion compartment, a series of draft tubes of varying lengths extending downward from said air inlet openings, and 80 a draft opening in the cover to allow egress for the generated gases.

3. An orchard heater comprising a fuel reservoir, a preliminary combustion compartment within the reservoir, a cover fitted 85 on the fuel reservoir, a draft opening in said cover, a series of air inlet openings in said cover located directly above the combustion compartment, a damper for closing successively said air inlet openings, a series 90 of draft tubes of varying lengths extending downward from said air inlet openings, and a perforated draft tube or chimney extending upward from the draft opening in the cover of the fuel reservoir. 95

4. An orchard heater comprising a fuel reservoir, a preliminary combustion compartment within the reservoir, a series of air inlet tubes adapted to admit air for preliminary combustion at or near the surface 100 of the fuel at all times during combustion, a cover fitted on the fuel reservoir, a draft opening in said cover, a perforated draft tube or chimney secured to the cover of the fuel reservoir inclosing the draft opening, a 105 horizontal cross tube extending through the side walls of the reservoir, and a smaller internal draft tube connected to the cross tube and extending upward within the draft tube or chimney. 110

5. An orchard heater comprising a fuel reservoir, a cover fitted on said reservoir and having a series of air inlet openings therein, draft tubes of varying lengths extending downward from said air inlet openings, a means whereby one or all of said inlet openings may be closed, and a draft opening in the cover for the passage of generated gases. 115

In testimony whereof, I have signed my 120 name to this specification in the presence of two subscribing witnesses.

JAMES L. HAMILTON.
